HANDRAIL ASSEMBLY

Wenzel W. Thom, Wichita, Kans., assignor of one-half to Cecil D. Jones, Wichita, Kans.
Filed Aug. 22, 1960, Ser. No. 51,027
9 Claims. (Cl. 256—65)

The present invention relates to couplings for tubular sections, and more particularly to pipe couplings of the type used in handrail or guardrail structure or the like.

The present invention has for its most important object, the provision of a screw member having oppositely threaded portions, whereby after the vertical post of a handrail is fixed in position, the rail section may be disposed at any desired angle with respect thereto and the screw member simultaneously threaded into the post and rail section from a position therebetween to effect interconnection of the same.

It is another object of the present invention to provide railing structure as above described, wherein all of the coupling structure is independent of the rail section prior to assembly, and which may be coupled with a rail section at any point desired, thereby enabling the railing builder to purchase the rail sections in standard lengths from a supplier, since the same require no special work to adapt the pipe for use in a railing.

It is another object of the present invention to provide a railing structure wherein the coupling parts used for interconnecting the railings with the upright post, may be completely prefabricated in quantity without regard to any specific stairway, inasmuch as the same may be used at any desired point in any installation.

It is still another object of the present invention to provide railing structure as above described, wherein both the rail and the coupling parts may be prefabricated for installation at any construction site, and wherein the railing and upright post may even be pre-bored if desired, so that workmen at the site of construction of the railing need no special tools whatsoever for accomplishing the assembly, the only tool required being a wrench for tightening the coupling.

It is still another object of the present invention to provide structure as above described wherein means are provided as a part of the coupling structure which covers the actual threaded coupling member and its related elements such that, when the railing structure is assembled, a smooth, merging, symmetrical surface is presented which will not catch or tear the clothes of a person using the handrail and which further will not lacerate or injure the hands of a user.

Various other objects of the present invention will become apparent as the specification progresses, and various modifications and changes may be made to the present invention without departing from the spirit thereof. Such modifications and changes and additional objects are intended to be covered by the scope of the appended claims.

In the drawings:

FIGURE 1 is a fragmentary, side elevational view of a stairway and railing embodying the present invention;

FIG. 2 is a view partially in section and partially in elevation, of a railing assembly showing an upright post, two rail members and the coupling structure embodying the present invention;

FIG. 3 is a longitudinal, cross-sectional view through a coupling embodying the present invention;

FIG. 4 is an exploded isometric view of the coupling parts and fragments of the railing and upright post, showing the method of assembly; and

FIG. 5 is a cross-sectional view through a fitting of the kind shown in FIG. 4 showing details of construction thereof.

Referring now to the drawings, in FIG. 1 a stairway 10

2

is shown provided with a railing unit or assembly indicated generally by the numeral 12. Railing assembly 12 includes a first upright post 14 and a second upright post 16. Post 16 is spaced laterally and downwardly relative to post 14 due to the construction of stairway 10.

A first handrail 18 is provided which is coupled (not shown) to the upright posts 14 and 16, and extends in an inclined position therebetween. A similar lower handrail 20 is provided, coupled with the posts 14 and 16 in a like manner. A central rail, composed of a first rail section 22 and a second rail section 24, is provided intermediate the first handrail 18 and second handrail 20, the rail sections 22 and 24 being illustrated to show that successive sections 22 and 24 may be coupled to provide a continuous, long handrail. This is usually done by placing the ends of two sections, such as sections 22 and 24, in abutting relationship as shown and providing a plug extending into the respective abutting ends of the sections in a well-known manner not herein shown. The ends of each of the rail sections which are normally open, and the top ends of the vertical posts 14 and 16, are provided with end caps 26 which not only artistically finish off the rail, but present smooth surfaces to the hands of a user.

In FIG. 2, a vertical post 28 is shown, together with fragments of transverse rail sections identified by the numerals 30 and 32. In this illustration, coupling means indicated generally by the numeral 34, are shown for interconnecting upright post 28 with rail fragments 30 and 32.

In FIG. 3, for purposes of clarity of illustration, an upright post 36 is fragmentarily shown in cross section, connected by a coupling 34 to a rail member 38 indicated in cross section which is disposed in a 90° offset angular relationship to the post fragment 36.

By referring to FIGS. 3 and 4 together, it may be seen that upright post 36 and transverse rail 38, are provided respectively with openings 40 and 42. A pair of fittings 44 and 46 are provided respectively for openings 40 and 42, and the same may be seen by referring to FIGS. 4 and 5, to be generally cylindrical in shape. For purposes of description, only the fitting 44 will be fully described, and it is to be understood that fitting 46 is identical with fitting 44.

The cylindrical surface of fitting 44 is provided with a knurled portion 48 extending longitudinally thereof from one end, a raised portion 50 extending longitudinally thereof from the other end and a shoulder 52 separating knurled portion 48 from raised portion 50. Fitting 44 is further provided with cuts 54 and 56 extending longitudinally into knurled portion 48, the cuts being disposed in planes running through the longitudinal axis of fitting 44. Cuts 54 and 56 terminate in spaced relationship to shoulder 52 and in the particular illustrated embodiment, divide the knurled portion 48 into quadrant end segments 58, 60, 62 and 64. Fitting 44 is further provided with a threaded axial opening 66 extending longitudinally therethrough from the end of fitting 44 surrounded by raised portion 50. Threaded axial opening 66 terminates at its point of junction with cuts 54 and 56 in a tapering frusto-conical cam surface 68 which in turn joins with cuts 54 and 56. It may, therefore, be seen that when a threaded member is inserted into the axial opening 66, it will progressively threadably engage the fitting, contacting the cam surface 68 to spread the end segments 58, 60, 62 and 64.

Referring again to the structure of FIGS. 3 and 4, it may be seen that if the knurled end 48 of fitting 44 is inserted into opening 40, the shoulder 52 will engage the exterior surface of post 36, while the knurled surface 48 will engage the margins of opening 40 such that when the end segments 58 through 64 have been spread, the fitting 44 will be fixed in opening 40 of post 46 against both axial and rotational movement.

An elongated screw member 70 is provided for interconnecting the fittings 44 and 46 after the latter have been emplaced in post 36 and rail 38. Screw member 70 consists of a central polygonal section 72, and oppositely extending, oppositely threaded screw portions 74 and 76. It may now be seen that screw member 70 may be placed between a post 36 and rail 38, and simultaneously threadably engaged with the latter by simply turning the screw member 70 by coupling a tool used for that purpose with the central polygonal section 72.

It should be pointed out at this point, that if desired, the openings 40 and 42 may be threaded to receive the screw member 70, thereby dispensing with the necessity for fittings 44 and 46, if such is desired. Also, while the use of such structure in a handrail for joining an upright post with a transverse rail, is the particular embodiment of the present invention chosen for illustration, the same coupling structure could equally well be used to couple two rail members or sections, neither of which is fixed at the time of coupling.

It should be further understood at this point that although the post and rail sections illustrated, are all shown to be cylindrical in the embodiments illustrated, the sections could be square or any other tubular section. Further, solid rail and post sections could be used if desired, simply by tapping the same to receive a screw member 70 if such proved desirable.

In order to provide a symmetrical covering for the coupling structure thus far described, a generally cylindrical tightener sleeve 78 may be provided having an opening 80 extending axially therethrough which is complementary in cross section to central section 72 of screw member 70. Tightener 78 may be telescoped over screw member 70 into interengaging relationship with the central section 72 thereof, and because of the complementary shapes of the central section 72 and the opening 80, relative rotational movement between tightener 78 and screw member 70, will be prevented. As shown at 82, tightener 78 may have its outer cylindrical surface adapted to receive a spanner wrench or other similar hand tool, so that when the tightener 78 is in place on central section 72, rotation of tightener 78 by an appropriate hand tool, will also rotate screw member 70. In the particular embodiment illustrated, tightener 78 is provided with shoulders 84 and 86 at each end, having a smaller diameter than the central portion 88. The reasons for shoulders 84 and 86 will become apparent as the description proceeds.

In order to further provide the symmetrical surface previously described as being desirable, a pair of frusto-conical copings 90 and 92 may be provided for telescoping assembly over the threaded portions 74 and 76 of screw members 70, and over the portions of fittings 44 and 46 which protrude from pipe 36 and rail 38 when the coupling is assembled.

Copings 90 and 92 have a diameter at one end the same as the diameter of central portion 88 of tightener 78, the diameter of the copings 90 and 92 increasing as the opposite end of the coping is approached. Copings 90 and 92 are provided with openings 94 and 96 extending axially therethrough. Openings 94 and 96 are of sufficient diameter to receive the raised portions 50 of fittings 44 and 46. The ends of the copings 90 and 92 which have the same diameter as central portion 88 of tightener 78, are disposed when the coupling is assembled, on opposite sides of the tightener 78 and copings 90 and 92 are provided with enlarged recesses 98 and 100 for receiving shoulders 84 and 86 of tightener 78.

The ends of copings 90 and 92 remote from tightener 78, are concave as at 102 and 104 in the embodiment shown for purposes of merging symmetrically with the cylindrical exterior surface of post 36 and rail 38. It should, of course, be understood that the formation of the ends of the frusto-conical sections which are remote from tightener 78, may be varied dependent upon the shape of the post and rail members to be engaged.

It may now be seen that the copings 90 and 92 may be emplaced about the threaded portions 74 and 76 of screw member 70 on opposite sides of tightener 78 and with the shoulders 84 and 86 of tightener 78 received in the recesses 98 and 100 of copings 90 and 92. The threaded portions 74 and 76 of screw member 70 may then be threadably engaged with fittings 44 and 46 and tightener 78 may be rotated to join the post 36 and rail 38. As the coupling is drawn up tight, the post 36 and rail 38 will be received in the concavities 102 and 104 of copings 90 and 92 and the entire coupling arrangement will, by virtue of the presence and shape of tightener 78 and copings 90 and 92, have a smooth symmetrical surface and appearance. Naturally, the shoulders 84 and 86 and the recesses 98 and 100 above described, could be eliminated and the copings 90 and 92 simply tightened into abutting relationship with tightener 78 if such was desirable.

Having thus described the invention what is claimed

- 20 as new and desired to be secured by Letters Patent is:
  1. A handrail assembly comprising a first pipe section having an opening therein; a second pipe section having an opening therein; fitting means fixedly retained in each of said openings, said fitting means each having a threaded opening therethrough; an elongated screw member having a central section and oppositely extending, oppositely threaded screw sections whereby said screw member may be simultaneously threadably engaged with said fitting means for coupling said pipe sections in any desired angular relationship; a tightener having an opening therethrough complementary to said central section of said screw member, said tightener telescopingly receiving said central section of said screw member to prevent relative rotation of said screw member and said tightener and thereby to rotate said screw member when said tightener is rotated; and a pair of coping means having openings therethrough, said coping means being telescoped over said fitting means and corresponding screw sections at the ends of said tightener whereby when said tightener and screw member are rotated to tighten said pipe sections together in any desired angular relationship, said coping means are clamped between said tightener and respective pipe sections in covering relationship to said fitting means and screw member.
  2. A handrail assembly as set forth in claim 1, wherein said tightener is generally cylindrical and said coping means are generally frusto-conical whereby when said coping means and said tightener are clamped between said pipe sections, a symmetrical covering surface is presented over said fitting means and said screw member.
  3. A handrail assembly as set forth in claim 2, wherein said tightener is provided with shoulders of reduced diameter at each end thereof and the respective coping means are provided with complementary, shoulder-receiving, axial recesses at the ends of the same facing said tightener, said coping means having concave pipe-receiving surfaces at their respective ends remote from said tightener whereby, when said coping means and said tightener are clamped between said pipe sections, said tightener shoulders fit within said coping recesses and said pipe is received in said concave pipe-receiving surfaces, thereby forming a smooth, merging, symmetrical coupling.
  4. A handrail assembly including an elongated, normally upright first section; a second elongated section; and connector means securing the second section to the first section in spaced relationship therefrom, said connector means including an elongated screw member having oppositely threaded portions extending from opposed extremities of the member toward the central part thereof, said threaded portions of the member extending into the first and second sections respectively, tightener means surrounding said central part of the member and slidably longitudinally of the latter, said central part of the member and said tightener means having mutually cooperable, interengageable means thereon for preventing substantial

relative rotation therebetween, and cover means around the member between said tightener means thereon and proximal, opposed surfaces of the sections whereby the first and second sections may be disposed in any desired relative angular relationship and fixedly maintained in such relationship by rotation of the tightener means in a direction to thread said portions of the member into corresponding sections until the cover means are tightly clamped between the tightener means and opposed surfaces of the sections.

5. A handrail assembly as set forth in claim 4 wherein said first and second sections are of tubular configuration and each provided with a side wall having an opening therein for removably receiving a respective threaded portion of said member.

6. A handrail assembly as set forth in claim 5 wherein is provided fitting means positioned within each of said openings in the first and second sections, said fitting means each having a threaded bore therethrough complementally receiving respective threaded portions of the member.

7. A handrail assembly as set forth in claim 6 wherein said fitting means includes a generally cylindrical element having a threaded axial opening therethrough, the exterior surface of said element having a knurled portion extending longitudinally thereof from one end of the same, a raised portion extending longitudinally thereof from the other end of the same and a shoulder separating said raised and knurled portions, said element being provided with slots therein extending longitudinally into said knurled portion from said one end forming end segments permitting the spreading of said one end, said slots being disposed in planes running through the longitudinal axis of said element, said slots terminating in spaced relation to said shoulder whereby when the knurled end of said element is inserted into a tubular section, said shoulder abuts said tubular section, said knurled portion frictionally engages the margins of said opening and said end segments may be spread, fixing said element against axial and rotational movement in respective openings in the sections.

8. A handrail assembly as set forth in claim 4 wherein

35 40

said central part of the member is generally polygonal in cross section, and the tightener means is provided with a polygonal passage therethrough complemental with the exterior surface of said central part of the screw member, said tightener means being provided with means for receiving a tool for rotating said tightener means and thereby said screw member.

9. A handrail assembly comprising a first pipe section having an opening therein; a second pipe section having an opening therein; and connector means securing the second section to the first section in spaced relationship therefrom, said connector means including an elongated screw member having oppositely threaded portions extending from opposed extremities of the member toward the central part thereof, said threaded portions of the member extending into corresponding openings in the first and second sections respectively, a tightener surrounding said central part of the member and slidably longitudinally of the latter, said central part of the member and said tightener having mutually cooperable, interengageable, generally polygonal surfaces thereon for preventing substantial relative rotation therebetween, and a pair of copings slidably mounted on said threaded portions of the tightener and provided with opposed, outwardly facing end surfaces thereon adapted to complementally engage opposed proximal surfaces of the first and second sections respectively whereby the first and second sections may be disposed in any desired relative angular relationship and fixedly maintained in such relationship by rotation of the tightener in a direction to cause said portions of the member to move into corresponding sections until the copings are tightly clamped between the tightener and opposed surfaces of the sections.
